A. J. GUILL.
TOBACCO RECEPTACLE,
APPLICATION FILED FEB. 28, 1919.

1,383,935.

Patented July 5, 1921.

A. T. Gruill Inventor
By Geo. P. Kimmel Attorney

UNITED STATES PATENT OFFICE.

ANDREW J. GUILL, OF WINIFRED, MONTANA.

TOBACCO-RECEPTACLE.

1,383,935.

Specification of Letters Patent.

Patented July 5, 1921.

Application filed February 28, 1919. Serial No. 279,838.

To all whom it may concern:

Be it known that I, ANDREW J. GUILL, a citizen of the United States, residing at Winifred, in the county of Fergus and State 5 of Montana, have invented certain new and useful Improvements in Tobacco - Receptacles, of which the following is a specification.

This invention has for its object to provide an improved receptacle especially designed to contain smoking tobacco and provided with a valve controlled discharge port permitting a smoking pipe to be conveniently filled with tobacco from the receptacle.

15 Another object is the provision of a novel type of stirring or agitating arm actuated by the valve rod and movable in the zone of the discharge port, whereby the contents of the receptacle are agitated during the opening movement of the valve rod to insure uninterrupted flow of the tobacco through the discharge port.

25 With these and other objects in view as will appear as the description proceeds, the invention comprises the novel features of construction, combination and arrangement of elements which will be more fully set forth hereinafter and described in the claims appended hereto.

30 In the drawings:

Figure 1 represents a vertical sectional view through the tobacco receptacle,

Fig. 2 represents a horizontal sectional view through the standard below the receptacle looking downwardly upon the base plate,

Fig. 3 represents a perspective view of the valve rod and agitator element removed from the body of the receptacle, and

40 Fig. 4 represents an enlarged horizontal sectional view, partly broken away, through the valve rod and support for the agitator arm.

45 Referring to the drawings in detail, wherein similar reference numerals designate corresponding parts throughout the several views, the numeral 5 indicates the body of the receptacle which is supported upon a standard 6 mounted in an upright 50 position upon a base 7 carrying a laterally projecting plate 8. The surface of the plate is provided with a depression 9 receiving a removable tray 10 designed to receive and hold the particles of tobacco which accidentally fall thereon when filling a pipe.

The upper portion of the receptacle 5 is

open to permit the tobacco or other material to be introduced therein and a closure plate 11 is removably fitted upon the open end to protect the contents of the receptacle. The 60 rear wall of the receptacle is curved downwardly and forwardly as indicated at 12 to guide the tobacco toward the discharge port 13 and connects with the vertically disposed front wall 14. As clearly illustrated in Fig. 65 1, the discharge port in the receptacle bottom is located centrally above the tray 10 and in such spaced relation thereto as to afford adequate space for the reception of a pipe which may be arranged underneath 70 the port 13 to be filled with tobacco.

The passage of the contents of the receptacle through the port 13 is controlled by a vertically movable valve rod 15 having an enlarged conical lower terminal 16 constituting 75 a valve adapted to seat in the port 13 and prevent the passage of the contents of the receptacle therethrough. The upper terminal of the valve rod is slidably and loosely received within a tubular guide sleeve 17 80 formed integral with the upper part of the receptacle and a button or handle 18 is fastened to the extreme upper terminal of the rod exteriorly of the receptacle whereby the valve 16 may be conveniently operated to 85 uncover the port 13. A stop pin 19 is fastened intermediate the ends of the rod 15 and is adapted to engage the inner surface of the upper portion of the receptacle body to prevent complete withdrawal of the rod 90 therefrom.

In order to agitate the tobacco during the uncovering of the port 13, an agitator arm 20 is pivotally connected at 21 with a sleeve 22 confined upon the rod 15 between pins 95 23 and the arm is movable over the curved guide portion 12 of the receptacle body to cause the tobacco to move toward the port 13 during the movement of the rod. A supporting arm 24 is secured internally of 100 the receptacle body and is provided with a slotted lower terminal 25 loosely supporting the arm 20 and the latter is connected with the rod 15 in such manner that when the valve 15 is in closed position the agitating 105 arm 20 is supported in a substantially horizontal position whereas when the rod is elevated in the act of uncovering the port 13 to dispense the tobacco the agitator arm 20 is swung downwardly over the guide surface 12 causing the tobacco to flow toward 110 and through the port 13. In case the to-

bacco becomes clogged at the mouth of the port 13, the rod 15 may be further elevated so as to swing the extreme curved terminal 26 of the agitator arm directly over the port 13 and by slight movement of the rod which is permitted by its loose mounting the agitator may be vibrated so as to loosen and cause the tobacco to flow freely through the port.

10 The lower surface of the receptacle is provided with a circular boss 13^a arranged concentric to the port 13 and of such diameter as to be received within the pipe bowl as suggested in dotted lines in Fig. 1 and the terminal of the valve projects slightly below the boss permitting it to be used in conjunction with the boss in properly tamping or packing the tobacco.

What I claim is:

15 20 1. A tobacco receptacle including a body provided with a discharge port, and a vertically movable valve rod supported in said body provided with an enlarged lower terminal constituting a closure for said port

and being pointed to penetrate the contents 25 of the receptacle.

2. A tobacco receptacle including a body provided with a forwardly curved rear wall and a discharge port in the lower portion thereof, a vertically movable valve rod constituting a closure for said port, and a pivoted agitator arm carried by the valve rod and movable through the central portion of the receptacle and over the curved portion of the rear wall and said discharge port. 30 35

3. A tobacco receptacle including a body provided with a discharge port, a vertically movable loosely mounted valve rod constituting a closure for said port, an agitator arm pivotally secured to the rod, and a slotted supporting arm loosely supporting the agitator arm and normally supporting the latter in a substantially horizontal position in the lower portion of the body when the valve rod is in closed position. 40 45

In testimony whereof I affix my signature hereto.

ANDREW J. GUILL
